UNITED STATES PATENT OFFICE.

CHARLES MEHL, OF OMAHA, NEBRASKA.

TAG-HOLDER.

1,333,434.

Specification of Letters Patent.

Patented Mar. 9, 1920.

Application filed May 31, 1919. Serial No. 300,867.

To all whom it may concern:

Be it known that I, CHARLES MEHL, a citizen of the United States of America, residing at Omaha, in the county of Douglas 5 and State of Nebraska, have invented certain new and useful Improvements in Tag-Holders, of which the following is a specification, reference being had therein to the accompanying drawing.

10 The invention relates to tag holders and has for its object to provide a spring actuated holder which may be easily and quickly attached to a shipping crate and in such a manner as to bear against a shipping tag 15 and maintain the same in position.

A further object is to provide a shipping tag holder formed from a single piece of spring wire, said holder having a portion adapted to be secured to one of the slats of 20 the shipping crate and a V-shaped tag holding member having a right angled point adapted to be embedded in the slat and to pass through the eye of the shipping tag.

With the above and other objects in view 25 the invention resides in the combination and arrangement of parts as hereinafter set forth, shown in the drawings, described and claimed, it being understood that changes in the precise embodiment of the invention 30 may be made within the scope of what is claimed without departing from the spirit of the invention.

In the drawings:—

Figure 1 is a perspective view of the 35 shipping tag clamp showing the same applied to a slat of a shipping crate.

Fig. 2 is a perspective view of another form of tag clamp.

Fig. 3 is a further modified form of the 40 shipping tag clamp.

Referring to the drawings the numeral 1 designates a slat of a shipping crate and 2 the tag clamp. The tag clamp is formed from a single piece of spring wire bent so as 45 to form a transverse bar 3, the wire being bent as at 4, thereby forming rearwardly extending members 5, which members are coiled as at 6, which coils form spring means. After the coils 6 are formed the wire is again bent 50 so as to form members 7 at right angles to the members 5, said members 7 being bent at right angles as at 8 thereby forming portions 9 extending toward each other, which portions are in turn bent as at 10 so as to 55 form arms 11 and 12, the outer ends of which are twisted together as at 13. Mem-

ber 12 is bent so as to form a right angle inwardly extending sharpened lug 14, which lug is adapted to pass through the eye 15 of the shipping tag 16, the body of said tag 16 being disposed under the arms 11 and 12 and by the spring action of the coil springs 6 be prevented from displacement or becoming marred. The clamp as a whole is secured to the slat 1 by means of staples 17 which arch the bar 3, and are embedded in one side of the slat 1.

Referring to Fig. 2, in this form the bar 3^a is provided with an offset portion 3^b, said bar 3^a being secured to the slat 1 by means of 70 staples 3^c. The ends of the bar 3^a are bent as at 18 thereby forming members 19, which members overlie the sides of the slat 1 and have their ends coiled as at 20, thereby forming springs. After the wire has been bent 75 so as to form the coils 20 they are bent so as to extend forwardly forming portions 21, which portions 21 are substantially parallel to the face of the slat 1. Portions 21 form means for preventing side movement of the 80 clamp as a whole; after the portions 21 are formed the wire is again bent as at 22 so as to form members 23, which members are substantially parallel with the members 19, the wire then being again bent as at 24 so as to 85 form the portions 9^a. The further bending and structure of the tag clamp as shown in this form is the same as that shown in Fig. 1.

Referring to the form shown in Fig. 3 the clamp is provided with a U-shaped arched 90 member 25 which is secured to the slat by staples 26, the arms of the U-shaped member 25 being formed into coil springs 27, the wire being then bent so as to form members 28, which members are adapted to overlie the 95 sides of the slat, the wire being again bent as at 29 so as to form the portions 30, which portions are substantially parallel to the face of the slat. The portions 30 correspond to the portions 21 in the form shown 100 in Fig. 2 and the clamping member of the tag clamp is of the same construction as that shown in Figs. 1, 2 and 3.

It will be seen that a tag holder has been 105 designed which may be easily and quickly applied to a shipping tag and one wherein it will be possible to quickly attach or detach the tag. It will also be seen that the consignee's name may be placed on one side of a shipping tag, and the consignor's name 110 on the other side, then when the crate is delivered to the consignee and emptied, it will

only be necessary for him to raise the tag clamping member against the action of the springs 20, reverse the tag, place it under the clamp and allow the clamp to come down over the same with the pointed member 14 passing through the eye of said shipping tag.

The invention having been set forth what is claimed as new and useful is:—

- 10 1. A shipping tag clamp formed from a single piece of spring wire, said clamp comprising a transverse portion adapted to be secured to a slat of a crate, means for preventing rotation of said transverse portion, the ends of said transverse portion being bent at right angles and formed with portions adapted to overlie the sides of the slat, said wire being again bent so as to overlie the face of the slat, the wires then extending forwardly and converging, said converging wires having their ends twisted together thereby forming the tag clamping member for holding one end of the tag, said portions which overlie the sides of the slat preventing side movement 20 of the other end of the tag, and one of said converging wires being bent at right angle thereby forming a prong adapted to pass
- 15
- 20
- 25

through the eye of a shipping tag and embed in the face of the slat.

2. A shipping tag clamp formed from a 30 single piece of spring wire, said clamp comprising a portion adapted to extend transversely across a slat and be secured thereto, said transverse portion being provided with means for preventing rotation thereof, the 35 ends of the transverse portion being provided with coil springs and portions overlying the edges of the slat, the ends of the portions overlying the sides of the slats being bent so as to form converging arms disposed on the face of 40 the slat, said converging arms having their ends twisted together, one of said ends being bent at right angles and adapted to pass through the eye of a shipping tag and embed in the slat, said portions which overlie 45 the edges of the slat forming means for preventing the side displacement of the free end of the shipping tag and also increasing the flexibility of the member formed by the converging arms.

50 In testimony whereof I hereunto affix my signature.

CHARLES MEHL.
